SAW FILING DEVICE

Michael Orskog, Elmwood Park, Ill.

Application April 6, 1942, Serial No. 438,555

7 Claims.

(Cl. 76—36)

This invention relates to file holders and more particularly to saw filing devices, although certain features thereof may be employed with equal advantages for other purposes.

It contemplates more especially the provision of an improved file holder for sharpening saws and similar tools in a much more effective manner without entailing as much time or skill.

Saw blades of numerous cuts and types are utilized for many different operations. It is particularly necessary to sharpen wood saws on the job in that their constant use by a carpenter or other technician, renders it necessary to give the cutting edge constant attention.

Then, too, each technician such as a carpenter employs a different saw-cut adapted to his particular requirement and stroke. This requires adjustability in the file holding device so that various angles may be imparted to the cutting edge of the saw with precision and uniformity throughout the length thereof. Angular adjustment of the file holders and the utilization of a guide so that successive teeth will be uniform in any predetermined angularity enables the sharpening on the job with precision by those who are not especially skilled in use of sharpening operations. A file holder and guide has been provided as adjustable within a wide range to meet the dictates of any particular technician or the varied requirements in effectively utilizing hand or power saws.

One object of the present invention is to simplify the construction and improve the operation of devices of the character mentioned.

Another object is to provide a plurality of file holders that are capable of being spaced in angular adjustment so that one may be utilized as a guide for the other in sharpening saws and the like.

Still another object is to provide a plurality of file holders having calibrated adjusting expedients in conjunction with angular edges to set a file in any predetermined angle for saw blade sharpening purposes.

A still further object is to provide a manual file holder handle with angularly adjustable mounts that are capable of being spaced relative to each other to conform with numerous types of saw cutting edges to enable the effective sharpening thereof.

Still a further object is to provide a plurality of adjusting means for regulating the file holder mounts in conjunction with a manual saw sharpener.

Other objects and advantages will appear from

the following description of an illustrated embodiment of the present invention.

In the drawing:

Figure 1 is a side view in elevation of a device embodying features of the present invention.

Figure 2 is a front view in elevation of the device shown in Figure 1, part of the handle being broken away to enable an enlarged showing of the operative elements.

Figure 3 is a fragmentary rear view in elevation of a file holder mount and its horizontal adjusting element.

Figure 4 is a sectional view taken substantially along line IV—IV of Figure 3.

The illustrated embodiment comprises a manual grasping handle 10 which may be shaped or constructed from wood or other suitable material depending upon the choice of the user. The handle 10 is downwardly inclined relative to a horizontal offset shank 11 which flares outwardly as at 12—13 to merge with upstanding ears 14—15 that are spaced from each other beyond the width of the narrow handle 10.

The ears 14—15 confront each other and project above the surface of the shank 11 to freely receive an elongated screw 16 that is journaled for rotation in the ears 14—15. The screw 16 has oppositely pitched threads 17—18 provided thereon to extend from the opposite extremities thereof to the center 19 to effect the displacement of file holders as will appear more fully hereinafter.

In order to effect the rotation of the oppositely threaded rod or elongated screw 16, a circular disc 20 having a knurled periphery 21 is attached to one extremity of the elongated screw 16, in this instance beyond the ear 14, to enable the manual rotation thereof and effect the opposite displacement of file holder mounts that are operatively connected thereto.

To this end, file holder mounts 22—23, in this instance two, comprise tubular cylindrical members (Figure 4) that are sized to receive the tapered shank 24 of suitable files 25 which, in this instance, are of triangular cross-section.

Plurality set screws 26, 27 and 28, in this instance three, threadedly engage correspondingly shaped apertures provided radially through the tubular mounts 22—23 to engage the file shank 24 along the length of the mounts 22—23 and at various angles relative to each other. In this instance, the radially defined set screws 26—27—28 are equidistantly disposed along the mounts 22—23 at 90 degree angles to effectively grasp the file shank 24 against any possible accidental movement or displacement. It should be noted that

the mounts 22-23 have projecting top extensions 29 which serve to engage the upper flat extremity of the triangularly shaped files 25 in order to index such relative to the mounts 22-23.

As shown, the mounts 22-23 merge with an enlarged threaded annular shoulder 30 which merges with a plane cylindrical surface 31 of corresponding diameter. The plane cylindrical surface 31 terminates in a large periphery flange 32 which serves as an abutment for angle control plates 33-34. The angle control plates 33-34 are preferably welded or otherwise attached to the mounts 22 against the peripheral flange 32 so that the mounts 22-23 will rotate with the angle control plates 33-34. The mounts 22-23 carry collars 35 on the smooth cylindrical shoulder 31 in a position adjacent the angle control plates 33-34. Upstanding guide plates 36-37 have apertures 38 corresponding in size with the smooth annular shoulder 31 of the file holder mounts 22-23. A nut 39 engages the threaded annular shoulder 30 of each of the file holder mounts 22-23 to engage against the upstanding guide plates 36-37 in order to maintain the parts in assembled predetermined relation. The nuts 39 are preferably of circular configuration and have a peripheral knurl 40 thereon to enable the convenient and effective finger rotation thereof.

When the nuts 39 are turned tight against the upstanding guide plates 36, peripheral flanges 32 of the mounts 22-23 are drawn together to hold the angle control blades 33 and their respective file holder mounts 22-23 in predetermined angular position. In order to adjustably support the mounts 22-23 and provide for the angular adjustment thereof to any predetermined degree, the guide plates 36-37 terminate downwardly in horizontally offset brackets comprising spaced ears 41-42 and 43-44 formed integrally with upstanding guide plates 36-37, respectively. The spaced ears 41-42 of the upstanding guide plates 36 are horizontally apertured and threaded as at 45 to mesh with the threads 47 on the elongated screw 16 journaled between the confronting handle ears 14-15. Similarly the spaced ears 43-44 of upstanding guide plate 37 are correspondingly perforated and threaded as at 45 to mesh with the threaded portion 48 of the elongated screw 16 so that manual rotation of the knurled disc 20 will cause the upstanding guide plates 36-37 to approach or recede from each other so that they are at a corresponding distance from the center 19 of the elongated screw 16, thereby correspondingly spacing the file holder mounts 22-23 which move therewith as a part of the upstanding guide plates 36-37.

To preclude the rotary displacement of the upstanding guide plates 36-37 relative to the elongated screw 16, the ears 41-42 and 43-44 thereof are apertured as at 46 in horizontal spaced relation to the threaded aperture 45 (Figure 4), to receive a guide rod 47 therethrough. The guide rod 47 bridges the ears 14-15 to serve as a guide rod for the upstanding guide plate brackets 41-42 and 43-44, thereby preventing the tilting of the file holders 22-23 in a clockwise or counter-clockwise direction relative to the handle 10 when viewed from Figures 1 and 4 so that the file holder mounts 22-23 may be adjusted to any desired predetermined position of rotation. So that the files 25 will be at a corresponding angle, the upstanding guide plates 36-37 are provided with elongated vertical slots 48 therethrough. The slots 48 are provided with

suitable graduations 49 that are calibrated to determine the angle at which the file holder 22-23 will be disposed when displaceable guide pins 50 or 51 are aligned with any particular graduation 49 along the slots 48 of the upstanding plates 36-37.

To this end, the guide studs 50 project from square collars 51 which have oppositely projecting trip studs 52 corresponding to and in horizontal alignment with the guide studs 50 (Figure 4). It should be noted that the oppositely projecting studs 52 project within the plane of the angle control plates 33-34 which have substantially V-shaped notches 53 communicating with the top edges thereof. The oppositely extending studs 52 project within the substantially V-shaped notches 53 so that their converging edges will engage one side or the other of the studs 52 serving as tripping means for the angle guide control plates 33-34. This will throw the file holder mounts 22-23 to a corresponding angle depending upon the vertical position of the oppositely projecting studs 50-52 serving as guide tripping means in conjunction with the polygonal collars 51. The vertical position of the polygonal collars 51 is determined by a vertical elongated screw 54 which is carried between a horizontally offset top flange 55 of the vertical guide plates 36-37 and the collars 35 on the shoulders 31 of the file holder mounts 22-23. To this end, the lower extremities of the elongated vertical screws 54 are provided with reduced ends 56 lodged in correspondingly sized recesses 57 provided in each of the collars 35 of the file holder mounts 22-23.

The upper extremities 58 of the vertical elongated screw 54 comprise reduced extensions which project through the horizontally offset guide plate flanges 55 to receive a knurled adjusting disc 59 attached thereto for effecting the rotation thereof. Consequently, the knurled adjusting screws 59 for each of the vertical guide plates 36-37 raise or lower collars 51 having an internal bore threaded mesh with the elongated vertical screws 54. It should be noted that the studs 50 may be provided with a horizontal indicator line or notch 60 to align with any of the desired graduations 49 along the slots 48 in the vertical guide plates 36-37. The graduations 49 are preferably calibrated in degrees so that the rotation of the knurled adjusting disc 59 in one direction or the other will raise or lower the oppositely projected studs 50-52 with their intermediate vertical collar 51.

When the indicator notch 60 on the studs 50 are aligned with the calibration 49 of the desired angle for holding the files 25, the file holder mount nuts 39 are loosened to permit the mounts 22-23 together with their angle control plates 33-34 to be rotated so that one or the other of the converging edges 53 contact against the studs 52 and determine the angle position of the file holder mounts 22-23. Thereupon, the nuts 39 are again tightened to maintain the file holder mounts 22-23 with their files 25 at the desired angle. The spacing of the file holder mounts 22-23, in turn, is determined by the elongated horizontal screw 16 which may be rotated in one direction or the other by the knurled adjusting disc 20. This spaces the files 25 with their mounts 22-23 to correspond with the spacing of the teeth on the saw cutting edge. Consequently, the saw cutting edge can be sharpened by utilizing one of the files 25 as a guide while the other file serves to sharpen the tooth aligned therewith to a corresponding

angle. The files 25 are thus engaged with successive teeth on the saw cutting edge until they are all uniformly sharpened to the desired angle with one file 25 serving as a guide for the other or others depending upon the number of mounts 22-23, in this instance two, that may be desired for any saw sharpening operation.

The reverse angle saw teeth on the cutting edge, may be correspondingly filed by reversing the angularity of the files 25 and their holders 22-23. For that reason, the angle control plates 33-34 are provided with converging edges defining the substantially V-shaped notches 53 so that one or the other may engage the studs 52 in order to adjust the file holders 22-23 not only to the desired angle, but also to enable filing of oppositely inclined teeth that are alternately disposed along a saw cutting edge.

With the arrangement of parts above described it will be apparent that a very simple and effective file holder for manual sharpening purposes has been provided wherein the initial angular adjustment can be set and thereafter the file holder mounts are rotatably displaced to the limit of movement for preadjustment. This insures accuracy, without entailing constant observation by the attendant. Most carpenters and other technicians utilizing equipment of this character are not in a position to observe their adjustment with any degree of accuracy because of poor lighting conditions and, of course, poor eyesight may be a factor among carpenters and others in analogous trades. The instrument can be set in one position where light is available and thereafter adjustments completed without any particular observation because of the limiting character of the angle control plates. Speed, uniformity, and accuracy in the sharpening operation is obtained without any appreciable skill or experience.

This structure is also suitable for circular saw sharpening. To adapt such to circular saws, one file 25 must correspond with the tooth groove. In the case of a circular wood saw, the teeth grooves are arcuate so that a round file would be used as a guide and a flat file for the actual sharpening operation. One holder 23 could be provided with a round file while the other holder 22 with a flat file. For circular metal saws, there would be a requirement for other shapes of files to correspond with special teeth configuration.

While I have illustrated and described a preferred embodiment of this invention, it must be understood that the invention is capable of considerable variation and modification without departing from the spirit of the invention. I, therefore, do not wish to be limited to the precise details of construction set forth, but desire to avail myself of such variations and modifications as come within the scope of the appended claims.

I claim:

1. In a sharpening device of the character described, the combination with a handle member, of a screw journaled on said handle member, threads of opposite pitch on said screw rod file holder mounts threadedly connected to said screw rod, file holders rotatively connected to said mounts, means for fastening said holders in any position of rotary adjustment relative to said mounts, angular guides fixed to said file holder mounts, and guide tripping means mounted for displacement along a predetermined path within the limits of said angular guides to determine the limiting angle set for said file holder mounts.

2. In a sharpening device of the character de-

scribed, the combination with a handle member, of file holder mounts rotatively connected to said handle member, file holders rotatively connected to said mounts, means for fastening said holders in any position of rotary adjustment relative to said mounts, angular guides fixed to said file holder mounts, guide tripping means mounted for displacement along a predetermined path within the limits of said angular guides to determine the angle set for said file holders means for displacing said guide tripping means to change the limit of angularity for said file holder mounts, and means for retaining said file holders in any adjusted angular position.

3. In a sharpening device of the character described, the combination with a handle having confronting members extending therefrom, of a single screw rotatively mounted between said confronting handle members, file holder mounts threadedly engaging said screw means on said handle, and means for rotating said screw to simultaneously vary the relative spacing of said file holder mounts symmetrically of said handle to correspond with spaced teeth of a cutting edge.

4. In a sharpening device of the character described, the combination with a handle member, of a file holder mount pivotally connected to said handle member, a plurality of files in said holder mount, an angular limit stop adjustably mounted on said handle member to cooperate with said file holder mount to control the pivotal position thereof relative to said handle member, and means for adjusting said angular limit stop to determine and control the pivotal displacement of said file holder mount to correspond with the teeth cutting angles.

5. In a sharpening device of the character described, the combination with a handle, of a threaded rod rotatively mounted on said handle, file holder mounts threadedly engaging said threaded rod, a plurality of file holders pivotally associated with said mounts, means on said threaded rod for effecting the rotation thereof to vary the relative spacing of said file holder mounts so that the files therein will engage correspondingly spaced teeth of a cutting edge, and means for varying the angular position of said file holders to correspond with the cutting angle of saw teeth and the like.

6. In a sharpening device of the character described, the combination with a handle member, of a rod having a series of threads of opposite pitch on portions thereof, said rod being rotatively mounted on said handle member, a plurality of file holder mounts threadedly engaging each series of threads on said rod, and means to rotate said rod for simultaneously effecting the displacement of said file holder mounts relative to each other.

7. In a sharpening device of the character described, the combination with a handle member, of a rod having a series of threads of opposite pitch journaled in said handle member, a plurality of parallel mounts threadedly engaging each series of threads of said rod, file holders pivotally associated with said mounts, and means to rotate said rod in opposite directions for effecting the simultaneous parallel displacement of said file holders and mounts relative to each other, and means for retaining said holders in any adjusted pivotal position on their respective mounts.

MICHAEL ORSKOG.
